(57) **CLAIM**

The ornamental design for a carrier pouch, as shown and described.

DESCRIPTION

FIG. 1 is a front elevational view of a carrier pouch showing our new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a left side perspective view thereof in a closed position;

FIG. 8 is a left side perspective view thereof, similar to FIG. 7, but with the pouch in an open position;

FIG. 9 is a front elevational view of a second embodiment thereof

FIG. 10 is a right side elevational view of the embodiment of FIG. 9;

FIG. 11 is a right side elevational view of the embodiment of FIG. 9;

FIG. 12 is a rear elevational view of the embodiment of FIG. 9

FIG. 13 is a bottom plan view of the embodiment of FIG. 9;

FIG. 14 is a top plan view of the embodiment of FIG. 9;

FIG. 15 is a left side perspective view of the embodiment of FIG. 9; and,

FIG. 16 is a left side perspective view of the embodiment of FIG. 9, similar to FIG. 15, but with the pouch in an open position.
